BAG ASSEMBLY

Clarence W. Vogt, Norwalk, Conn.

Application August 25, 1948, Serial No. 46,057

7 Claims. (Cl. 229—53)

1

This invention relates to bag assemblies and more particularly to bags which are connected together in a chain as by one or more flexible tapes extending lengthwise of the bags as disclosed in my copending application, Serial No. 38,477 filed July 13, 1948.

The filling and sealing of non-rigid containers such as bags formed or lined with flexible material and particularly thermoplastic films such as "cellophane," "saran," polyethylene or "pliofilm," with a measured quantity or weight of material, involves a cost of packaging often disproportionate with respect to the cost of the material being packaged, unless these operations can be performed automatically at a relatively high rate of speed and with a minimum of supervision and handling.

Where end folded bags of the above type have flaps or other extra material integral therewith and utilized to aid in the opening of the mouths thereof for filling, and are also used in sealing the bags to form airtight, moisture and water-proof containers, such flaps add materially to the cost and weight of the bag where thousands of bags are to be filled, and the added weight increases the expense of handling and shipping.

The invention involves a chain of bags spaced apart endwise and connected in series by one or more lengths or strips of tape, which are used to open the mouths of the bags to enable the bags to be filled, sealed and ejected from the filling machine described hereinafter.

In a preferred embodiment herein chosen to illustrate my invention, means are provided to effect step by step movement of a chain of bags connected by two lengths of tape and move said bags past said operating stations, which function only after each intermittent movement and when the bags are stopped at said operating stations.

The operations performed at said stations include the opening of the bag, the charging of the latter with a predetermined amount or weight of material, the stripping away of one of the connecting tapes, the sealing of the open mouth of the loaded bag, the stripping away of the other of the connecting tapes and the ejection of the loaded bags from the machine.

In the accompanying drawings there is shown only one of the various possible embodiments of the several features of the invention.

Fig. 1 is a fragmentary side elevational view of the apparatus partly in cross section.

Fig. 2 is a fragmentary end elevational view of the apparatus partly in cross section taken along line 2—2 of Fig. 1.

2

Fig. 3 is a view similar to Fig. 2 taken along line 3—3 of Fig. 1.

Fig. 4 is a perspective view of one of the bags.

Fig. 5 is a transverse sectional view of two bags in superposed relation and

Fig. 6 is a fragmentary perspective view of another embodiment of the bag.

Although various types of cams, gears and sprocket wheels or other mechanisms may be employed for operating the constituent elements of the machine in timed relation, and there are many possible ways of driving them from a motor, or other source of power, a particularly desirable arrangement is shown in the drawings.

Referring now to Figs. 1 and 2, the machine comprises a frame 11 at the upper end of which is mounted a substantially L-shaped bracket 12, the vertical leg 13 of which is secured to frame 11, for instance, by screws 14.

Bracket 12 has a downwardly extending flange or panel 15 at the free end of its horizontal portion 16 to which is affixed by screws or bolts 17, a filling device 18, which may be conventional in construction and need not be described except to the extent necessary for a complete understanding of the novel features of the invention.

The filling device 18 has a main drive motor M with a vertical drive shaft 19 provided with a pair of spaced sprocket wheels 22 and 23. The sprocket wheel 22 is connected by a chain 24 to a sprocket wheel 25 which is affixed to vertical shaft 26 which controls the filling mechanism (not shown), to discharge a fixed quantity or weight of material from hopper 27 through outlet nozzle or spout 28.

Sprocket wheel 23 is connected by a chain 29 to a sprocket wheel 32 affixed, as by set screw 33, to a vertical stud shaft 34 rotatably mounted and secured at its upper end 35 in a bearing 36 in the horizontal portion 16 of bracket 12.

The lower end 37 of the shaft 34 has a bevel gear 38 affixed thereon by set screw 39, said gear 38 meshing with an associated bevel gear 41 affixed on a transverse shaft 42 and rotatably mounted on the frame of the machine.

Shaft 42 also has a disk 43 affixed thereto which forms part of a Geneva drive mechanism. This disk 43 has a finger 44 projecting radially from the periphery thereof to which is affixed a laterally extending pin 45, the latter coacting with the notched rim of a drive disk 46 affixed by set screw 47 to transverse shaft 48. The latter is journaled at one end as at 51 in a bearing 52 in frame 11 as shown in Fig. 2 and near its other end in a bearing 53 provided in laterally extend-

ing bracket 54, the latter having a vertical leg 55 affixed to frame 11 by screws 56.

Illustratively, there are four notches 57 in drive disk 46 so that four complete revolutions of disk 43 are required for one complete rotation, in intermittent 90 degree steps, of shaft 48 to which disk 46 is affixed. It is of course to be understood that more or less notches could be provided in disk 46 depending upon the rate of output desired for the machine.

Also mounted on shaft 48 and affixed thereto by set screw 61 is a gear 62 which meshes with an associated gear 63 affixed by set screw 64 to a hollow transverse shaft 65. The latter is journaled at one end in a bearing 66 in frame 11 and near its other end in a suitable bearing 67 provided in bracket 54, and there is provided a heating element 70 positioned in the bore of shaft 65.

Shaft 65 also has affixed thereon by set screw 68 a large gear 69, as well as a cam plate 71, the latter having a plurality of cam surfaces 72, illustratively three in number, on the periphery thereof. Also mounted on shaft 65 is a drum 73, having a plurality of projections serving as sealing surfaces 74, illustratively three in number, extending radially from the periphery 75 thereof and aligned with cam surfaces 72 as is clearly shown in Fig. 1.

Rigidly affixed to filling device 18 and projecting therefrom is a bracket 81 to the free end of which is pivotally mounted a sleeve 82, through which extends an actuating rod 83. One end of rod 83 has a roller 84 mounted thereon which rides on the periphery of cam plate 71 as is shown in Fig. 1. A coil spring 85 is secured at one end as at 86 to the rod 83 and at its other end 87 to the sleeve 82, thereby normally resiliently urging said rod through said sleeve to retain the roller 84 against the periphery of cam plate 71.

The free end of rod 83 is pivotally connected as at 88 (Fig. 3) to a lever 89, the latter having a hub 91 at its free end in which is affixed a transverse rod 92. The free end of the latter is rigidly connected as at 93 to one wall of a substantially U-shaped pouring funnel 94, the latter being pivotally mounted on the outlet 28 by laterally extending studs 95 rigidly affixed to the side walls of the funnel and positioned in openings 96 therein, the funnel 94 straddling the outlet 28 for the purpose hereinafter set forth.

Gear 69 meshes with a gear 97 affixed by set screw 98 on hollow transverse shaft 99, the latter having a heating element 80 positioned in the bore thereof. Shaft 99 is journaled at one end in a bearing 101 in frame 11 and near its other end 100 in a bearing 102 provided in a laterally extending bracket 103, the latter having a vertical leg 104 affixed to frame 11 by screws 105.

The end 100 of shaft 99 extends beyond bearing 102 and has a drum or roller 106, affixed thereto as is clearly shown in Fig. 2, roller 106 having a peripheral groove 107 therein, as well as an indexing pin 108 extending radially outward from the surface thereof.

Gear 97 on shaft 99 meshes with an idler gear 111 affixed by set screw 110 on a transverse shaft 112, the latter being journaled at one end in bearing 113 in frame 11 and at its other end in a bearing 114 provided in bracket 103.

Idler gear 111 meshes with a gear 115 affixed by set screw 116 to transverse shaft 117, the latter being journaled at one end in a bearing 118 in frame 11 and near its other end 119 in a bearing 121 provided in bracket 103.

The end 119 of shaft 117 extends beyond bearing 121 and has a drum or roller 122, affixed thereto, the latter having a peripheral groove 123 therein aligned with peripheral groove 107 in roller 106, as well as an indexing pin 124 extending radially outward from the surface thereof and aligned with pin 108 on roller 106.

Gear 115 through meshed pinions 125 and 126, drives a gear 127 affixed on a transverse hollow shaft 128 rotatably mounted on the frame 11 as is shown in Fig. 1. Shaft 128 has a heating element 130 positioned in the bore thereof and carries a drum or roller 129 and which is aligned with rollers 106 and 122.

Roller 129 also has a peripheral groove 131 therein (see Fig. 3), which is positioned to the left of the groove in rollers 106 and 122 for the reason hereinafter set forth.

Positioned between rollers 106 and 122 and mounted on frame 11 is an inclined table 135 having parallel side walls 137 which serve to guide the bags being filled. A second inclined table 138 mounted on frame 11 is also provided to guide the filled bags onto a conveyor belt 139 which discharges the bags from the machine.

The machine above described is adapted for automatic operation in the filling of a chain or series of bags such as 141 and 141'.

One of such bags 141 is shown in Fig. 4 and has opposed inverted pleats 142 along the side edges thereof and the bag 141' as shown in Fig. 6 is of the "pillow case" type with parts corresponding to the bag of Fig. 4 having the same reference numerals primed.

As shown in Fig. 4 the bottom of the bags are closed by folding over the lower end portion 143 thereof and sealing such folded ends. The bags are spaced apart endwise and connected, preferably by two longitudinal tapes 144 and 145, which extend lengthwise of the bag one on each side thereof. The tapes are preferably laterally offset as shown in Figs. 4 and 5 so that in rolling the chain of bags on a roller 147, the strips will not be superposed. Such superposing would cause a bulge in the center of the roll and reduce the number of bags which would be put on a single roll.

In order to provide for proper indexing of the bags when they are fed through the machine in the manner hereinafter described, tape 145 is desirably provided with a plurality of openings 146 therein positioned in the space between the bags to receive indexing pins 108 and 124 as will hereinafter be described.

The bags may be of paper or similar material in which case they are provided at their open ends with inwardly facing surfaces formed of, or coated with, a sealing material which may be of non-tacky latex which will seal upon closing of the mouth of the bag and application of pressure thereto, or of a thermoplastic film so that when heat and pressure are applied, the mouth of the bag will be closed and sealed.

The thermoplastic material may be in the form of strips extending along and around the inner surface of each bag at its mouth or the bags themselves, as illustratively shown herein may be made of a thermoplastic material. Sheets or tubes of a heat sealing "cellophane" such as made and sold by Du Pont, "Pliofilm" such as made and sold by Goodyear, films of a polyvinylidene chloride such as made and sold by Dow Chemical Co., under the trade-mark "Saran" and polyethylene such as sold by Plax Corporation and Visking Corporation, are suitable materials for the bags.

Some thermoplastic material such as films of polyvinylidene chloride greatly shrink when subjected to such heating as will permit heat sealing. If such shrinkable material be employed in making the bags, a stiffening strip is preferably applied along or over the mouth portion, and which will adhere to the "Saran" and prevent the latter from shrinking during sealing of the bags. Such stiffening strips may be applied to the outer surface of each bag mouth prior to or at the time 10 the heat and pressure are applied to soften and stick the layers or "Saran" and bag walls together.

It is to be noted that the making of the entire bag of thermoplastic material is preferred where the bags are to be filled with material which is to be non-porous so as to protect the contents from dirt, dust or moisture.

The tapes 144 and 145 which join the bags are preferably spot sealed by adhesive material to the bags only near the upper end thereof as shown at 161 and 162. There are many types of materials that could be used for the tapes thus, for example, if the bags as well as the tapes are of paper, a coating of non-tacky latex could be applied to each which would only adhere when in contact, or if a thermoplastic bag was used, the tape could be of the type known as "Scotch tape" which could readily be sealed on the bag. Preferably, as illustratively shown herein, the tapes are of delayed action thermoplastic coated paper of the type put out by the Nashua Gummed and Coated Paper Company under the trade-marks "Thermo-kote" or "Thermo-stix" which tapes are activated by heat and then applied under pressure. The characteristics of this material is such that the sealing surface of the tape will be non-tacky and non-adhesive when cold and when reactivated by heat will become tacky and remain so for a period of time up to several hours.

Thus, after the tapes have served their purpose, the temperature at the sealing area may be raised to the required degree to soften the adhesive and thereupon the tapes may be peeled off to free the individual filled and sealed bags.

Operation

The operator when setting up the machine for operation unrolls a length of the chain of thermoplastic bags from the roll 150 which is mounted on shaft 150. The tape 145 is positioned in the groove 123 in roller 122 with indexing pin 124 in an opening 146 in the tape. The tape is then passed over table 135 and around roller 106 being positioned in the groove 107 therein with indexing pin 108 extending through another opening 146 in the tape.

Tape 144 which is identical with tape 145 except that it need not have an opening 146 therein, is positioned in the groove 131 in roller 129 and passed around said roller.

In order positively to pull on tapes 144 and 145 to ensure the passage of the bags through the machine, two pairs of take-up rollers 170, 171 and 172, 173 are provided associated with tapes 144 and 145 respectively and gripping such tapes. The rollers are operatively connected by a suitable transmission (not shown) with shaft 48 and will rotate in timed relation along with said shaft.

The hopper 27 is filled with the material to be discharged into the bags and the heating elements 70, 80 and 130 in shafts 65, 99 and 128 respectively are energized in order that they may heat sealing surfaces 74 and rollers 106 and 129 respectively.

Motor M which will rotate continuously, is thereupon turned on to begin the automatic operation of the machine which is as follows:

Rotation of motor M and shaft 19 driven thereby, will rotate sprocket wheel 23 and through sprocket chain 29 and sprocket wheel 32, drive shaft 34. This will rotate bevel gear 38 which in turn drives bevel gear 41 to rotate shaft 42 and disk 43 thereon in a clockwise direction.

As disk 43 rotates, pin 45 will engage one of the four notches 57 in drive disk 46 at each complete revolution of disk 43, thereby stepping drive disk 46 through 90° or one quarter of a revolution. Thus shaft 48 to which drive disk 46 is affixed will also move one quarter of a revolution in a counterclockwise direction, as will gear 62 affixed thereon.

Gear 62 which meshes with gear 63 on shaft 65 will thereupon rotate the latter in a clockwise direction along with drums 75, and gear 69 thereon.

Gear 69 which meshes with gear 97 on shaft 99 will rotate the latter in a counterclockwise direction along with roller 106 affixed on said shaft. Gear 97 through idler gear 111 mounted on shaft 112, which gear 111 meshes with gear 115 on shaft 117 will rotate the latter in a counterclockwise direction, along with roller 122 thereon.

30 Gear 115 through pinions 125 and 126, which latter pinion meshes with gear 127 on shaft 128, will rotate the latter and roller 129 thereon, in a clockwise direction.

At the same time as shaft 48 rotates, take-up 35 rollers 170, 171 and 172, 173 which are operatively connected thereto will also rotate to pull on tapes 145 and 144 respectively to move the bags carried thereby to the opening, filling and sealing stations.

40 It is to be noted that with the indexing pins 108 and 124 in upright position as shown in Fig. 1 and in opening 146 in the tape, a bag 141 at position A will be directly below the funnel 94 of the filling machine and by reason of the fact that 45 the tapes 144 and 145 are spaced when positioned around roller 122 and 129 the mouth of the bag will be pulled open.

With bag 141 at position A, roller 84 on rod 83 will be against the low portion of the rim 50 of cam 71 and hence lever 89 will have pivoted rod 92 so that funnel 74 will be in pouring position as shown in full lines in Fig. 1.

55 The filling mechanism (not shown) in filling device 18 which is driven by sprocket wheel 27, sprocket chain 24, sprocket wheel 25 and vertical shaft 26, is timed to function through conventional timing mechanism (not shown) only when funnel 94 is in pouring position and will deliver a fixed charge at such time.

As shaft 65 rotates through the transmission heretofore described, the cam surface 12 will abut against roller 84 to move rod 83 so that funnel 94 is pivoted to closed position as shown in dot and dash lines in Fig. 1, while at the same time the filling mechanism in filling device 18 will not be activated.

At the same time take-up rollers 170, 171 and 172, 173 will be driven to pull on tapes 144 and 145. As roller 129 has been heated by the heating element 130 and as the thermoplastic spot seal 161 which is of relatively small size, is against said roller, the activated tape will become tacky and as the tape 144 is wound around roller 129 it will peel off the bag if the tape is coated with 76 a "delayed action" type of thermoplastic. In

order to prevent the activated tape from sticking to roller 173, the latter may be coated or covered with a silicone coating to which the actuated thermoplastic will not adhere.

As tape 145 is pulled by rollers 170, 171 it will draw the filled bag from the filling station beneath the outlet 28 up inclined table 135. The bags are so spaced on the tape that a 90° revolution of the shaft 48 through the transmission heretofore described from the Geneva drive mechanism, will move the bag from station A to station B where the mouth of the bag will be against heated roller 106 and will also move an empty bag from position C to the filling station at position A while at the same time opening said bag. The sealing members 74 on drum 73 are so spaced thereon that when the bag is against roller 106 one of the sealing members will have closed the mouth of the bag and be exerting pressure thereagainst. As both the roller and sealing member are heated, the mouth of the thermoplastic bag will be sealed and the activated spot seal 161 of tape 144 to said bag will become tacky.

At the same time rod 83 will have been retracted by cam 71 to move funnel 94 to pouring position and the filling device 18 will eject a charge of material into the empty bag at position A.

As shaft 48 makes another 90° revolution under the drive from the Geneva drive mechanism, tape 144 will move the bag from the sealing station at position B onto table 138 at the same time moving the filled bag from the filling station at position A to position B and moving an empty bag from position C to position A.

It is to be noted that as tape 145 is drawn around roller 106 and bag 141 is discharged onto table 138 the activated spot 162 on tape 145 will peel away from said bag to free the latter from the tape.

Although two tapes are shown applied to bags 141, tape 144 could be dispensed with and the bag opened for filling by applying a suction cup to the free side of the bag or by blowing air into the mouth of the bag or by any other suitable means. In such case, roller 129 and take-up rollers 172, 173 and their actuating means could be dispensed with.

It is also within the scope of this invention to dispense with the heating elements entirely and use self-stick material for the spot seal of the bag to the tapes and also for the mouth of the bag. This self-stick material requires only pressure for sealing and of the tape thus coated also may readily be peeled off a correspondingly coated spot on the bag in the same manner as previously described with respect to the actuated thermoplastic tape but without the use of heated rollers.

It is also within the scope of this invention to use short strips or tabs, similar to those shown at K of Fig. 3 of my co-pending application Serial No. 38,477 filed July 13, 1948, but with the strips or tabs joining the bottom of one bag with the top of an adjacent bag to form a chain of bags, and removing such tabs after they have served their chaining function, or leaving them on for convenience in packing multiples of the filled bags in shipping containers, leaving the later severance to be accomplished by the dispenser.

Although in the machine herein shown and described an intermittent drive is utilized, it is of course to be understood that the Geneva

drive mechanism could be dispensed with and a continuous drive utilized. It will be understood that while the bags may be disposed with their mouths facing in different directions when rolled up as shown in Figure 1 or otherwise stacked, to supply them to the filling machine, they nevertheless face in the same direction when the chains are unrolled or unstacked. In such case it would only be necessary properly to time the machine so that the feeding device and sealing members would operate at the required time. As the application of such a drive mechanism, in view of the disclosure herein made is readily apparent, no further description thereof will be given.

The machine herein can operate for many hours without supervision requiring as it does only an adequate supply of material and bags, and as there are but few operating parts, the possibility of breakdown is remote thus increasing the efficiency and hence the output of the machine.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. As an article of manufacture a plurality of bags connected in series by a pair of elongated tapes on opposite side walls extending lengthwise of said bags at right angles to the mouth thereof, said tapes being unconnected with each other and spot sealed to opposite sides of each bag by a reactivatable delayed action thermoplastic at a restricted zone adjacent to the mouth of said bag to retain all the bags in substantially parallel relationship with their mouths facing in the same direction, said bags being openable independently for filling by pulling one tape away from the other.

2. In combination, a plurality of bags arranged in a row with the bags extending lengthwise of the row, spaced apart, and having their mouths facing in the same direction, and a pair of tapes one on each side of said row, each tape being secured to the respective side walls of each bag adjacent to the mouth thereof, whereby said bags may be fed in succession to a filling station by moving said tapes endwise, and the bag mouths may be opened by moving one of said tapes away from the other.

3. A construction as defined in claim 2, and in which the securing of the tapes to the bags is effected by an adhesive permitting said tapes to be freed from each bag by pulling said tapes away from each other after the mouth has been opened.

4. A construction as defined in claim 2, and in which said tapes have apertures therein for registry with tape advancing means.

5. A construction as defined in claim 2, and in which the tapes are laterally offset in respect to each other and in opposite directions in respect to the longitudinal center line of the sides of said bags.

6. A construction as defined in claim 2, and in which the sealing of the tapes to the bag walls is at comparatively small spots.

7. A construction as defined in claim 2, and in which the tapes and bags are wound up in a roll with the tapes and bags extending circumferen-

9

tially of the roll, and the tapes being spaced apart in the direction of the axis of the roll.

CLARENCE W. VOGT.
